933,032. SEWING-MACHINE. CHARLES F. GRAY, Sierra Madre, Cal., assignor to The Singer Manufacturing Company, a Corporation of New Jersey. Filed June 11, 1909. Serial No. 501,456.

To all whom it may concern:

Be it known that I, CHARLES F. GRAY, a citizen of the United States, residing at Sierra Madre, in the county of Los Angeles and State of California, have invented certain new and useful Improvements in Sewing-Machines, of which the following is a specification, reference being had therein to the accompanying drawings.

This invention relates to that class of stitching machines designed to produce both straight-away and zigzag stitching in a continuous seam, for closing shoe uppers, stitching "patch pockets" to garments and performing various operations upon overalls

and other articles of clothing to which this class of combination seam is particularly applicable.

As shown and described in the United States patents to Thomas W. Morrison, No. 216,289, dated June 10, 1879, and Thomas F. Hart and George S. Hill, No. 406,277, dated July 2, 1889, it has long been common to construct sewing machines for producing combined straight-away and zigzag seams by the use of a jogging needle with controlling means for throwing into and out of operation the needle-jogging means, devices being employed for preventing the change between straight-away and zigzag stitching excepting upon a particular stitch of a series or succession of stitches and at a stage of the stitch-producing cycle in which the point of the needle was out of the work; so that the straight-away stitching would be invariably produced in alinement with the same one of the extreme needle punctures of the zigzag stitching, and the change from one to the other kind of stitching would be accomplished at a time when the work could not be injured or the needle broken by lateral movement of the needle while in the fabric. The present invention is not therefore directed broadly to needle-jogging mechanism capable of being changed at the will of the operator for producing either straight-away or zigzag stitching while the machine is in motion, nor is it addressed broadly to means for timing the changes between straight-away and zigzag stitching to any particular stitch of a series or succession of stitches or to any particular stage of a stitch-producing cycle; but it consists in certain specific devices for controlling the needle-jogging mechanism whereby the convenience and effectiveness of operation of machines of the class described are increased.

In the accompanying drawings, Figure 1 is a front side elevation of a machine embodying the present improvements, and Fig. 2 a sectional plan view of the same taken partly through the axis of the main-shaft and partly through that of the cam-shaft and controlling rock-shaft. Fig. 3 is a detail elevation of the needle jogging devices. Fig. 4 is a rear side elevation of the machine and Fig. 5 a similar elevation showing the jog-controlling mechanism in a different position. Figs. 6 and 7 are rear face views of the controlling cam respectively in releasing and locking positions, and Figs. 8 and 9 are vertical sections through the same and the cam-shaft upon which they are mounted.

The machine is constructed with the usual bed-plate 1 with overhanging bracket-arm 2 upon the head 3 of which is disposed the horizontal fulcrum-stud 4 upon which is journaled the swinging needle-bar frame 5 provided in its lower portion with a trans-

verse slot 6 to receive the headed guide-stud 7 upon the lower member of the head 3 of the bracket-arm. In the lateral bearing members 8 of the needle-bar frame 5 is journaled the vertically reciprocating needle-bar 9 carrying the needle 10 and provided with the fixed collar 11 carrying a stud embraced by one end of the pitman 12 whose opposite end embraces a crank-pin upon the crank-plate 13 fixed upon the forward end of the main-shaft 14 which is journaled as usual in the bracket-arm and provided at its rearward end with the balance-wheel 15.

As herein represented the needle 10 co-operates with the rotary lock-stitch hook 16 mounted upon the transverse shaft 17 connected by suitable gearing with the longitudinal shaft 18 mounted beneath the bed and driven by means of the belt 19 and sprocket-wheels 20 from the main-shaft 14.

Upon the main-shaft 14 is fixed the angular gear-wheel 21 meshing with the larger angular gear 22 fixed upon the transverse cam-shaft 23 which is thus rotated at one-half the speed of the main-shaft. The cam-shaft carries the so-called "triangular" cam 24 which is embraced by the parallel members 25 of a yoke 26 formed at the forward end of a link-bar 27 pivotally connected at its rearward end by means of the screw-pin 28 with a lug 29 upon the needle-frame 5.

As will be observed, the link-bar 27 receives vibratory movements upon its pivotal connection 28 from the actuating cam 24, but is free to move endwise in relation to said cam. In order that the sidewise actuation imparted by the cam may be partially converted into endwise movement, the link-bar is provided adjacent its yoke 26 with a controlling stud 29 which is provided with suitable guiding means for determining its path of movement.

As herein shown, the guiding means comprises the swinging link 30, one end of which embraces the controlling stud 29 of the link-bar 27 and the other end embraces a fulcrum-stud 31 carried by a lateral arm 32 fixed upon the transverse rock-shaft 33 journaled in the rearward side of the bracket-arm parallel with the cam-shaft 23. The rock-shaft 33 is disposed slightly below and forwardly of the cam-shaft 23, and in such position that its axis is at substantially the same level, and preferably coincident with that of the controlling stud 29 when the link-bar 27 is in its extreme lower position.

The controlling rock-shaft 33 has fixed upon its rearward end the lateral crank-arm 34 forked at its outer end to embrace a pin 35 upon the forward end of a lever 36 fulcrumed upon the fixed stud 37 upon the bracket-arm and formed in its lower side with a socket 38 entered by the upper threaded end of a push-rod 39 provided with a

thrust-nut 40 between which and the guiding boss 41 of the bracket-arm is interposed a spring 42 by means of which the arm 36, and consequently the arm 34, is yieldingly maintained in raised position. The crank-arm 34 is provided with a lug 43 having an eye in which is hooked the upper end of the treadle-rod 44, adapted for drawing such arm downwardly to rock the shaft 33 in opposition to the spring 42.

When the arm 34 is in its normal or upper position, as represented in Fig. 4, the fulcrum-stud 31 for the swinging link 30 is disposed upon an imaginary line joining the centers of the shaft 23 and pivotal screw-pin 28, so that the vibration of the link-bar 27 carries the controlling stud 29 across such line at substantially right angles, and hence it receives no appreciable endwise motion through the guiding link 30; but when the arm 34 is drawn downwardly into the position represented in Fig. 5, the rocking of the shaft 33 carries the fulcrum-stud 31 above such imaginary line, whereby the link 30 is caused to swing across said line obliquely, thus producing an endwise movement of the link-bar 27 in addition to its uniform side-wise movement, this endwise movement being communicated to the swinging needle-frame 5 and producing jogging movements of the needle in conjunction with its reciprocating movements.

As will be observed, the cam 24 is provided with outer and inner concentric portions or dwells *a* and *b* each covering an arc of substantially a quarter circumference, the extremities of these portions being joined by inclined actuating portions *c* and *d*. As will be observed, the engagement of the concentric portions *a* and *b* with the embracing members 25 of the yoke 26 serves to retain the link-bar immovably in upper or lower position while the needle descends through the work and emerges therefrom, while the eccentric or live portions *c* and *d* accomplish the throw of the link-bar in one or the other direction while the needle is out of the goods. In any case, according to the arrangement shown in the drawings, the movement of the link-bar to extreme lower position causes the link 30 to overlie the fulcrum carrying arm 32, and their extremities to lie in substantially the same line, whereby the endwise position of the link-bar and hence the position of the needle is caused upon each alternate stitch to assume initial relation, regardless of the position of the arm 32 and the fulcrum-stud carried thereby. By this construction and arrangement of parts it will be seen that in the initial or neutral position of the fulcrum-stud 31 in which the link-bar 27 receives no appreciable endwise movement, the needle-bar is maintained in initial or straight-away stitching position through-

out the production of consecutive stitches and when the arm 32 is shifted to throw the fulcrum-stud 31 out of alignment with the cam-shaft and pivotal pin 28, the needle-frame will still assume initial or straight-away stitching position when the link-bar is in its extreme lower position, but will be drawn inwardly into what may be termed edge-stitch position, when the link-bar is thrown into upper extreme position. This is true regardless of the position in which the fulcrum-stud 31 is set for a given width of zigzag stitch or overseam, because the rock-shaft 33 constituting the fulcrum of the arm 32 is in substantial alignment with the controlling stud 29 in one of its extreme positions, so that the fulcrum-stud 31 is always shifted in an arc concentric with such position of which the swinging link 30 forms a radius in the same extreme position of the link-bar 27. For this reason, when the link-bar is in the extreme lower position to which it is thrown by the cam 24, the rocking of the shaft 33 to shift the fulcrum-carrying arm 32 produces no effect upon the position of the link-bar 27, as the members 30 and 32 overlie each other and the pivotal points of their ends remain substantially coincident in all positions of the fulcrum-stud 31.

In order to regulate the range of movement of the lever-arm 34, the rear side of the bracket-arm is shown provided with the spaced lugs 45 and 46 in each of which is inserted a stop-screw 47 with lock-nut 48, the points of the upper and lower stop-screws being adapted to engage the upper and lower edges, respectively, of the spring-pressed lever 36 to limit respectively its upper or initial position and its lower or jog-stitch position, the range of movement of this lever determining that of the arm 34 of the rock-shaft 33, and hence of the arm 32 and fulcrum-pin 31 carried thereby.

The rearward end of the cam-shaft 23 is formed with a cylindrical socket 49 within which is slidably fitted the shank 50 of a controlling cam-disk 51 having upon its inner or forward face two screw-pins 52 whose heads 53 are normally seated upon the bottoms of countersink holes 54 in a thrust-collar 55 secured upon the rearward end of the shaft 23 by means of set-screws 56. A spring 57 is interposed between the inner end of the shank 50 of the cam disk and the inner end of the socket 49, whereby the cam-disk is yieldingly pressed into its extreme rearward position, which is determined by the heads of the stop-screws 52. The outer or rearward face of the cam-disk 51 is shown provided with a diametrical groove or recess 58 having abrupt segmental side-walls concentric with the axis of motion of the cam-disk to form stop-shoulders 58^a and laterally and outwardly inclined ends 58^b ar-

ranged at an angle with the axis of motion of the cam-disk convergent with the beveled edge portions 59 of the cam-disk whose outer periphery is otherwise cylindrical so as to form externally of said recess segmental stop-shoulders circularly coextensive with the shoulders 58^a, as indicated in Figs. 6, 7 and 9. The lever arm 34 carries upon its front face a stud 60 which, in the normal elevated position of the arm 34, is disposed substantially concentric with the cam-disk 51, and extends within the transverse groove or recess 58 therein. The cam-disk 51 is so set upon the shaft 23 in relation to the actuating cam 24 that when the yoke 26 first reaches the limit of its extreme upper or lower throw, and the needle is rising and its point is a little above the work, the groove 58 is substantially vertical, so as to permit the descent of the locking stud 60 from normal concentric position with the crank-arm 34, but as the cam-shaft continues to rotate and the needle rises to its highest position, the groove 58 is brought into varying angular relations with the circular path of movement of the stud 60 upon the crank-arm 34, and serves to restrain the movement of the latter by one of its segmental stop-shoulders 58^a until the cam-disk has made substantially a semi-rotation, and the transverse groove 58 again assumes substantially a vertical position as the yoke 26 attains its opposite extreme position, and the point of the needle is again above the work and rising to extreme elevated position, when the stud 60 is again free to move downwardly with its supporting arm 34 in shifting the fulcrum-stud 31 for effecting the change between straight-away and zigzag stitching conditions. When the yielding cam 51 is in releasing position, as indicated in Fig. 6, the drawing down of the lever-arm 34 causes the stud 60 in its descent to engage the inclined end portion 58^b of the groove 58, thereby causing the thrusting aside of the cam-disk in opposition to its spring 57, but the continued descent of the stud past the transverse cam-rib afforded by the convergently beveled portions 58^b and 59 permits the cam to return under the action of the spring 57 into its normal position, the stop-shoulder afforded by the angular edge of the cam-disk locking the stud 60 in its lower position and preventing the immediate return of the arm 34, to initial straight-away stitching position under the action of its returning spring 42.

The restraining and releasing action of the lever-arm 34 just described is obviously due to the construction and relation of the component parts of the yielding cam-disk 51 which rotates with the actuating cam 24 and the stud 60 constituting the follower therefor which has a segmental path of movement in a plane at right angles to the axis of

movement of the cam-disk. As the path of movement of the stud 60 is thus substantially at right angles to the stop-shoulders afforded by the cylindrical walls 58^a of the recess 58 and the cylindrical peripheral portion extending through a corresponding arc, it is evident that these parts have a positive engagement without producing any tendency to relative lateral movement transversely of their normal directions of movement; but as the end portions of the recess or depression 58 of the cam-disk and the convergent peripheral bevels 59 are inclined both to the axis of movement of the cam-disk and the path of movement of the stud 60 upon its carrying arm 34, the engagement of the stud with the cam-shoulders 58^b or 59 is of a yielding character, owing to the yielding relation of the cam-disk 51 to its supporting and actuating cam-shaft 23, whereby a relative lateral movement is produced between such interengaging parts in opposition to the action of the spring 57.

When it is desired to change from the zig-zag stitching position of the parts represented in Fig. 5, the release of the treadle-rod 44 permits the spring 42 to press the levers 36 and 34 upwardly with the stud 60 resting against the periphery of the cam-disk 51 until one of the beveled portions 59 of the disk encounters the stud 60, when the latter is permitted to ride up the same, thereby forcing aside the cam-disk until it enters the recess 58 and returns to normal position therein, when the cam-disk resumes normal operative position, and the lever 34 is again intermittently confined in initial straight-stitching position. It will be observed that the construction of the controlling or locking cam 51, and its action upon the operating lever 34, is such that said lever is free to be manually operated through the treadle-rod 44 whenever the needle is raised above the work, regardless of its lateral position and that of the needle-frame through which it receives its sidewise or jogging movements.

From the foregoing description, it will be seen that the actuation of the controlling lever 34 to shift the movable fulcrum 31 of the swinging link 30 may be properly effected at any time during the stitch-producing cycle while the link-bar 27 is in its lower position, corresponding with the straight-away stitching or "depth-stitch" position of the needle, as in such position of the link-bar 27 the fulcrum-pin 31 can move upon its carrying arm 32 only in a path concentric with the controlling stud 29. It is equally evident that the position of the lever 34 may be changed at any time while the point of the needle is above the work on either the "depth stitch" or "edge stitch" cycle without injuring the work or endangering the

breakage of the needle. It will therefore be apparent that only one side of the cam-disk 51 is essential to insure against the change between straight-away and zigzag stitching, and this is the side provided with the shoulder 58^a and the corresponding external peripheral shoulder occupying a position at the lower side of the groove 58 during the time when the link-bar 27 is in its upper position and the needle is in the work. The particular form of the cam 51 is not thus material so long as it is provided with the inner and outer stop-shoulders and adjacent inclines or cam portions for engaging respectively the sides and end of the stud 60 carried by the controlling lever 34; while it is equally immaterial which of these interengaging parts is made capable of yielding transversely of the direction of operative movement of the cam-disk, so long as they are adapted for relative yielding movement whereby the one may thrust aside the other to permit the free movement of the lever 34 crosswise of the direction of operative movement of the cam-disk after the stud 60 has completed its normal period of engagement with the respective stop-shoulder of the cam member.

It is evident that, unless the lever 34 is rocked to change the position of the fulcrum-stud 31, the machine is adapted for producing plain stitching. In case it is desired to lock the parts in such manner as to produce zigzag or overseam stitching only, it is merely necessary to depress the levers 34 and 36 and to lock them in this position. According to the present invention, a locking plate 61 is mounted at one end upon the fulcrum-stud 37 and is provided intermediate its ends with a transverse slot 62 entered by the clamp-screw 63 tapped into the lever 36. The lever 36 having been shifted into jogging position as before described, the clamp-screw 63 is loosened and the free end of the locking plate 61 is set in contact with the lug 45 or adjusting screw 47 and the clamp-screw retightened, by which means the lever 36 is prevented from rising under the action of its spring 42, as indicated in dotted lines in Fig. 5.

I have herein referred to the swinging member 5 in which is journaled the reciprocating needle-bar as a "needle-frame", but it is to be understood that by the term needle-frame is intended any equivalent sidewise moving member so connected with the needle as to communicate thereto its sidewise or jogging movements. In previous structures, the needle has in some instances been carried by the needle-bar journaled in a laterally swinging needle-frame, as in the present construction, and in other cases the needle has been directly carried by a sidewise movable frame or carrier mounted upon

a rectilinearly reciprocating needle-bar not partaking of the sidewise or jogging movements of such frame or carrier. As, according to the present invention the nature of the connection between the jogging mechanism and the needle is not material, it is to be understood that this improvement is equally adapted to either of these prior forms of construction.

Having thus set forth the nature of the invention, what I claim herein is:—

1. In a sewing machine, the combination with stitch-forming mechanism comprising a reciprocating needle, a coöperating loop-taker and actuating means for said needle and loop-taker, continuously acting means for imparting lateral jogging movements to said needle, and a controller acting on the needle-jogging means whereby the effective action of the needle-jogging means may be neutralized, of interengaging parts comprising a cam-member carried by a moving part of the machine and comprising a stop-shoulder and an adjacent relatively inclined cam-portion, and a stud movable with said controller relatively to said cam-member and adapted for positive engagement with said stop-shoulder and yielding engagement with the adjacent cam-portion of the cam-member, one of said interengaging parts being mounted to yield transversely of the directions of normal movement of both so as to permit one to freely pass the other under the action of said inclined cam portion of the cam-member with the stud.

2. In a sewing machine, the combination with stitch-forming mechanism comprising a reciprocating needle, a coöperating loop-taker and actuating means for said needle and loop-taker, continuously acting means for imparting lateral jogging movements to said needle, and a controller acting on the needle-jogging means whereby the effective action of the needle-jogging means may be neutralized, of a cam-member yieldingly mounted upon a moving part of the machine and comprising a stop-shoulder and an adjacent relatively inclined cam-portion, and a stud movable with said controller relatively to said cam member and adapted for engagement with said stop-shoulder and adjacent cam-portion of the cam-member.

3. In a sewing machine, the combination with stitch-forming mechanism comprising a reciprocating needle, a coöperating loop-taker, and actuating means for said needle and loop-taker, continuously acting means including a rotary actuating cam for imparting lateral jogging movements to said needle, and a controller acting on the needle jogging means whereby the effective action of the needle-jogging means may be neutralized, of a rotary cam-member movable with and circularly adjustable in relation to said

actuating cam and comprising a stop-shoulder and an adjacent relatively inclined cam-portion, and a stud movable with said controller relatively to said cam-member and adapted for positive engagement with said stop-shoulder and yielding engagement with the adjacent cam-portion of the cam-member.

4. In a sewing machine, the combination with stitch-forming mechanism comprising a reciprocating needle, a coöperating loop-taker and actuating means for said needle and loop-taker, continuously acting means including a rotary actuating cam for imparting lateral jogging movements to said needle, and a controller acting on the needle-jogging means whereby the effective action of the needle-jogging means may be neutralized, of an axially yielding rotary cam-member movable with and circularly adjustable in relation to said actuating cam and comprising a stop-shoulder and an adjacent relatively inclined cam-portion, and a stud movable with said controller relatively to said cam-member and adapted for engagement with said stop-shoulder and adjacent cam-portion of the cam-member.

5. In a sewing machine, the combination with stitch-forming mechanism comprising a reciprocating needle, a coöperating loop-taker and actuating means for said needle and loop-taker, continuously acting means for imparting lateral jogging movements to said needle, and a controller including a vibratory lever acting on the needle-jogging means whereby the effective action of the needle-jogging means may be neutralized, of a cam-member yieldingly mounted upon a moving part of the machine and comprising a stop-shoulder and an adjacent relatively inclined cam-portion, and a stud carried by said vibratory lever and adapted for engagement with said stop-shoulder and adjacent cam-portion of the cam-member.

6. In a sewing machine, the combination with stitch-forming mechanism comprising a reciprocating needle, a coöperating loop-taker, and actuating means for said needle and loop-taker, of a laterally movable needle-frame, a rotary cam-shaft, means for imparting to said cam-shaft a single rotation for each two complete reciprocations of the needle, an actuating cam on the cam-shaft, a link-bar pivotally connected at one end with the needle-frame and deriving swinging movements from said cam, a controlling stud upon said link-bar, a rock-shaft parallel with said cam-shaft and disposed in substantial alinement with the said controlling stud in one of the extreme positions of said link-bar, guiding means for said controlling stud connected to said rock-shaft and adapted to determine the direction of movement of the link-bar under the action

of said cam, a second axially yielding cam upon said cam-shaft provided with a radial groove having abruptly shouldered side-walls and reversely inclined end merging into the side face of the cam-member, an arm upon said rock-shaft, a stud upon said arm of the rock-shaft adapted to normally enter said groove in the second-named cam, and means for rocking said rock-shaft.

7. In a sewing machine, the combination with stitch-forming mechanism comprising a reciprocating needle, a coöperating loop-taker, and actuating means for said needle and loop-taker, of a laterally movable needle-frame, continuously acting means for imparting jogging movements to said needle-frame, and means connected with said needle-frame jogging means whereby the effective action of the needle-frame jogging means may be neutralized; and comprising a rock-lever, a rotary cam-disk formed with a radial groove having an outwardly and laterally beveled end portion and convergent bevel upon the periphery, said beveled portions of the cam-disk being arranged at an inclination to the axis of movement of the latter, means for imparting to said cam one rotation for each complete to-and-fro jogging movement of the needle-frame, a stud mounted upon said rock-lever to enter said cam-groove and yieldingly engage its outwardly inclined end portion and peripheral bevel, and means for shifting said rock-lever.

8. In a sewing machine, the combination with stitch-forming mechanism comprising a reciprocating needle, a coöperating loop-taker, and actuating means for said needle and loop-taker, of a laterally movable needle-frame, continuously acting means for imparting jogging movements to said needle-frame, and means connected with said needle-frame jogging means whereby the effective action of the needle-frame jogging means may be neutralized; and comprising a rock-lever, a rotary axially-yielding cam-disk formed with a diametrical groove with outwardly and laterally beveled end portions and convergent bevels upon the periphery, said beveled portions of the cam-disk being arranged at an inclination to the axis of movement of the latter, means for imparting to said cam one rotation for each complete to-and-fro jogging movement of the needle-frame, a stud mounted upon said rock-lever to enter said cam-groove, and means for shifting said rock-lever.

9. In a sewing machine, the combination with stitch-forming mechanism comprising a reciprocating needle, a coöperating loop-taker, and actuating means for said needle and loop-taker, of a laterally movable needle-frame, an endwise movable link-bar pivotally connected at one end with the

August 31, 1909
page 7

needle-frame, means for imparting to said link-bar uniform lateral movements about its pivot of which one in each direction is effected for every complete reciprocation of the needle, guiding means to determine the direction of movement of said link-bar under the action of its swinging means, a controlling rock-shaft by which said guiding means are carried, an arm fixed upon said rock-shaft and provided with means for moving it, and an adjustable stop for determining the throw of the rock-shaft arm.

10. In a sewing machine, the combination with stitch-forming mechanism comprising a reciprocating needle, a coöperating loop-taker, and actuating means for said needle and loop-taker, of a laterally movable needle-frame, a rotary cam-shaft, means for imparting to said cam-shaft a single rotation for each two complete reciprocations of the needle, a cam on the cam-shaft, a link-bar pivotally connected at one end with the needle-frame and having at its opposite end a yoke embracing said cam, a swinging link pivotally connected to said link-bar near said yoke, a rock-shaft parallel with said cam-shaft and disposed in substantial alignment with the pivotal connection of the swinging link to the link-bar in one of the latter's extreme positions, an arm fixed upon said rock-shaft, a fulcrum-stud upon said arm for said swinging link, a second arm fixed upon said rock-shaft, means applied thereto for rocking said shaft, and adjustable stops whereby the range of movement of the second-named rock-shaft arm in both directions may be limited.

In testimony whereof, I have signed my name to this specification, in the presence of two subscribing witnesses.

CHARLES FREDERICK GRAY.
